UNITED STATES PATENT OFFICE.

ALLAN S. BARROWS, OF CHICAGO, ILLINOIS.

SHEET-METAL FLUSH CAR-DOOR.

1,395,080.

Specification of Letters Patent. Patented Oct. 25, 1921.

Application filed September 10, 1917. Serial No. 190,500

To all whom it may concern:

Be it known that I, ALLAN S. BARROWS, a citizen of the United States, residing at Chicago, in the county of Cook and State of Illinois, have invented a certain new and useful Improvement in Sheet-Metal Flush Car-Doors, of which the following is a full, clear, concise, and exact description, reference being had to the accompanying drawings, forming a part of this specification.

This invention relates to improvements in sheet metal flush car doors.

One object of my invention is to provide an all-metal flush door more particularly adapted for use on railway box cars and having great strength to resist lateral thrusts in proportion to the weight of the metal employed.

Another object of my invention is to provide a door of the character above indicated which is adapted to be made from a single sheet of metal and have the edges and body portion thereof strengthened entirely by integral formations.

Another and more specific object of the invention is to provide a sheet metal door of the so-called flush type for railway cars which door is of minimum thickness, consistent with successful service, around its edges to thereby reduce to a minimum the depth of the recessing in the door frame by which the door is made flush and thus prevent the customary weakening of the door frame necessitated by the use of present thick wooden flush doors.

The invention furthermore consists in the improvements in the parts and devices and in the novel combination of the parts and devices herein shown, described and claimed.

In the drawing forming part of this specification, Figure 1 is a side elevation of a portion of a car showing one form of my improvements in connection therewith. Fig. 2 is a horizontal, sectional view upon a somewhat larger scale, of the structure illustrated in Fig. 1. Fig. 3 is an enlarged vertical, sectional view taken substantially on the line 3-3 of Fig. 1.

Referring to the drawing, 10 denotes the side wall of a wooden box car having the usual side door opening therein, said opening being defined by side posts 11-11, threshold 12 and lintel 13. My improved door is designated generally by the reference A.

Said improved door A, as shown, is made

of a single piece of sheet metal of comparatively small gage, $\frac{1}{8}$ " being sufficient for commercial practice. The door is of rectangular formation to correspond to the door opening and the sheet of metal 14 of which the door is made has the edges thereof doubled back closely upon itself, as indicated at 15-15 on the vertical side edges, at 16 along the top edge, and at 17 along the lower edge. By doubling the edges of the door as above described, the effective thickness thereof is equal to substantially twice the thickness of the sheet metal, that is, $\frac{1}{4}$ ", and extremely strong edges are thus provided well adapted to resist blows which might otherwise cause serious indentation, and without the necessity of employing any bracing beams with the consequent additional expense of punching and riveting. At the same time, the edges of the door are relatively thin and consequently the rabbets or recesses 18-18 in the door frame members can be made very shallow so that the door frame members are not weakened. Heretofore, in flush car door structures, the doors have been made relatively thick so that it has been necessary to cut away a relatively large proportion of the door posts and other members of the door frame with consequent weakening of the car structure. Also, in prior flush door structures, on account of the thick doors employed, the rabbeting to receive the same has had to be made considerably larger than the size of the door itself in order to permit the proper setting of the door in the event the door framing becomes distorted as frequently occurs in the operation of cars. My arrangement overcomes these difficulties as above pointed out.

In order to strengthen the door against lateral thrusts, particularly thrusts received from the lading within the car, the door A is provided with inwardly extended vertical ribs 70 and between the latter is dished inwardly, as indicated by the beveled or inclined portions 19-19 around the four sides of the door. As an additional strengthening means, the dished portion is provided with a series of outwardly extended preferably horizontal ribs or corrugations 20-20 although it will be obvious that other forms of corrugations and dishing may be employed to accomplish the same result.

For operating the flush door, the following mechanism is employed: Upper and lower tracks 21 and 22 are secured to the

outer face of the car and at its forward or advance end, the door A is provided at the top with a hanger bracket 23 and at the bottom with a corresponding bracket 24, 5 both being of well known or desired form. At its rear edge, the door is provided with a pair of bearings 25—25 in which is rotatably mounted an operating shaft 26, the latter being operated by a handle 27. At its 10 lower end, the shaft 26 is provided with a crank arm 28 in which is pivotally mounted about a vertical axis a bracket 29 which engages the lower track 22. At its upper end, the shaft 26 is provided with a similar 15 crank arm 28 in which is pivotally mounted about a vertical axis a combined supporting and roller-carrying bracket 30. Said bracket 30 is provided with a depending portion 31 rotatably mounted in the crank 20 28 and at its upper end has a laterally extended bearing 32 for the anti-friction roller 33. Above the roller 33, the bracket 30 is provided with a hood-like protecting flange 34. The door is shown in the drawing in its 25 closed or flush position. By rotating the shaft 26, it is obvious that the rear edge of the door will be drawn outwardly as the shaft swings about the brackets 29 and 30 after which the door can be moved to open 30 position. In order to positively insure the forward edge of the door being forced to flush position and to also prevent any danger of said portion of the door being sprung outwardly by shifting loads, the forward 35 edge of the door is provided with a plurality of wedge-shaped castings 35 which are adapted to engage the undercut surfaces 36 on a corresponding number of brackets 37 secured to the side of the car.

The door being made of relatively light 40 sheet metal, its total weight is comparatively small and with the integral strengthening features thereof render said door extremely strong and rigid, and on account of the thin edges, weakening of the door frame members 45 is avoided as heretofore pointed out.

I claim:

In a flush car door construction, the combination with a car wall having a door opening therein defined by wood framing, the 50 latter being provided with shallow rabbeting around the door opening on the outer side of the car wall; of a sheet metal door composed of relatively thin sheet metal of a single thickness except around the marginal 55 portions which consist of flat multiple-plies of sheet metal of a total thickness corresponding to the depth of said rabbeting, the sheet metal of the door, within said marginal portions, being provided with strengthening indentations to resist transverse 60 thrusts, said indentations producing a door of an effective over-all thickness greater than the thickness of said flat marginal portions, said indented portions of the door 65 being disposed inwardly of the outside plane of said flat marginal portions and extending within the door opening when said flat marginal portions are seated within said shallow rabbeting, whereby the depth of the rabbeting required in the wood framing is less than said effective over-all thickness of the door.

In witness that I claim the foregoing I have hereunto subscribed my name this 25th 70 day of Aug., 1917.

ALLAN S. BARROWS.
